PICKER STICK CHECK

Clarence H. Sanders, Bristol, Va.

Application February 25, 1954, Serial No. 412,498

8 Claims. (Cl. 139—164)

This invention relates to a picker stick check.

An object of the invention is to provide novel means for checking or retarding the movement of the picker stick at the end of its stroke.

Another object is to provide a check for picker sticks that will prevent any bending or hammering of the same, and which will prevent the rebound.

A further object is to provide a device of the kind described for holding the picker stick medially disposed with relation to the lay beam.

A more particular object is the provision of a picker stick check especially constructed for holding the picker stick under spring tension and preventing rebounding and chattering of the picker stick when it has reached its outward limit of movement.

Yet a further object is to provide a device of the character described which consists of a minimum number of parts and which provides easy means of adjustment of the parts.

Other objects will appear hereinafter throughout the specification.

In the drawings:

Figure 1 is a side elevational view of the picker stick check;

Figure 2 is a bottom plan view of the check shown in Figure 1 with certain of the parts shown in section; and

Figure 3 is an end elevational view of the structure shown in Figures 1 and 2.

In the accompanying drawing, my improved checking device is attached to the lay of the loom, not shown, that is provided with the usual picker stick, and this device is attached to the underside of one or both ends of the lay of the loom. The numeral 10 indicates a pair of supporting plates, or a single plate may be provided to take the place of said pair of plates. Said plates are provided with apertures 12 for attachment of the device to the underside of the lay. I prefer a pair of plates instead of a single plate for the purpose of regulating the relationship of the flat springs hereinafter described.

Each plate is provided with an upstanding boss 14 for mounting the main flat springs 16 whose inner sides are provided with pads of leather, rubber, or rubber-like material 18.

Means is provided for reinforcing and adjustably mounting the main flat springs. The reinforcing means comprises outer reinforcing springs 20, and an inner rocking plate 22.

Each rocking plate is composed of spring metal and is provided with a substantially centrally located bulge or hump 24, as seen particularly in Figures 2 and 3.

Each of the springs 16 and 20, and the inner rocker plate 22 and boss 14 is provided with spaced apertures for the reception of the screw bolts 26 having squared heads 28. A washer 30 may be interposed between each head 28 and its outer reinforcing spring 20. Only the apertures in bosses 14 need be screw threaded, the corresponding

2

apertures in the rocking plate 22 and springs 16 and 20 preferably being unthreaded apertures.

It will be noted that each spring 16 comprises a substantially straight portion 34 substantially parallel to the support, and a portion 38 at an angle thereto, the portions 38 converging toward each other to form a V 40.

Further, the springs 20 comprise straight, parallel portions 32 overlying portions 34 of springs 16, and angled portions 36 overlying part of portions 38 of springs 16

10 to reinforce said springs 16.

By reference to the structure particularly shown in Figure 2, it will be noted that tightening of the screw bolts 26 will cause each unit including its set of springs and leather covers mounted thereon, to move toward each other. The bulge in each inner rocking plate is gradually flattened as the screw bolts are tightened, and this bulge forms a resilient or spring-like mounting for each unit, as well as a rocker.

Moreover, should it be desired to change the angle of 20 each unit to provide a larger or smaller V-shaped recess, this may be accomplished by loosening one of the screw bolts of one unit slightly and tightening the other screw bolt of that unit. This adjustment will enable one to make a very accurate adjustment for the picker staff, 25 which moves into the V-shaped recess. This adjusting means is an important structural feature of the present invention.

From the foregoing, it will be obvious that when the shuttle is thrown and comes in contact with the picker on 30 the staff, said staff will be forced into the V-shaped opening 40, to be gradually retarding the speed of the shuttle until it arrives at the end of its race. This check, therefore, obviates to a large extent the necessity of binders, and greatly reduces the wear on the shuttle.

35 Accurate and effective adjustment is assured by the two ways of adjusting each unit; i. e., the tightening or loosening of both screw bolts 26 on each unit. Alternatively one screw bolt may be tightened while the other is allowed to remain untightened, or is moved in the opposite direction as the screw bolt of that unit. This latter action effects a rocking movement about the fulcrum of the bulge or raised portion 24.

40 The above description and drawings discloses a single embodiment of the invention, and specific language has been employed in describing the several figures. It will nevertheless be understood that no limitations of the scope of the invention are thereby contemplated, and that various alterations and modifications may be made such as would occur to one skilled in the art to which the invention relates.

50 I claim:

1. A check for picker sticks for looms comprising supporting means, a pair of main flat supporting springs, means mounting said springs adjacent one end on said supporting means, said mounting means including a pair of adjusting screws for each spring, and rocking means having an inwardly facing fulcrum portion located between each pair of screws and bearing against said supporting means, said springs having free ends extending 55 toward each other and forming a V-shaped recess.

2. A check for picker sticks for looms comprising a pair of supporting plates, a pair of main flat supporting springs, means mounting said springs adjacent one end on said pair of supporting plates, said mounting means including a pair of adjusting screws for each spring, and rocking means having an inwardly facing fulcrum portion located 60 between each pair of screws and bearing against said supporting means, said springs having free ends extending toward each other and forming a V-shaped recess.

3. A check for picker sticks for looms comprising sup-

porting means, a pair of main flat supporting springs, means mounting said springs adjacent one end on said supporting means, said mounting means including a pair of adjusting screws for each spring and rocking means having an inwardly facing fulcrum portion located between each pair of screws and bearing against said supporting means, said springs having free ends extending toward each other and forming a V-shaped recess, said rocking means comprising a plate located between each spring and said supporting means.

4. A check for picker sticks for looms comprising a pair of supporting plates, a pair of main flat supporting springs, means mounting said springs adjacent one end on said pair of supporting plates, said mounting means including a pair of adjusting screws for each spring, and rocking means having an inwardly facing fulcrum portion located between each pair of screws and bearing against said supporting means, said springs having free ends extending toward each other and forming a V-shaped recess, said rocking means comprising a plate located between each spring and one of said supporting plates.

5. A check for picker sticks for looms comprising supporting means, a pair of main flat supporting springs, means mounting said springs adjacent one end on said supporting means, said mounting means including a pair of adjusting screws for each spring, rocking means having an inwardly facing fulcrum portion located between each pair of screws and bearing against said supporting means, said springs having free ends extending toward each other and forming a V-shaped recess, and a reinforcing spring lying against each main supporting spring.

6. A check for picker sticks for looms comprising a pair of supporting plates, a pair of main flat supporting springs, means mounting said springs adjacent one end on said pair of supporting plates, said mounting means including a pair of adjusting screws for each spring, rocking means having an inwardly facing fulcrum portion located between each pair of screws and bearing against said supporting means, said springs having free ends extending toward each other and forming a V-shaped recess, and a reinforcing spring lying against each main supporting spring.

7. A check for picker sticks for looms comprising supporting means, a pair of main flat supporting springs, means mounting said springs adjacent one end on said supporting means, said mounting means including a pair of adjusting screws for each spring, rocking means having a raised portion located between each pair of screws, said springs having free ends extending toward each other and forming a V-shaped recess, said rocking means comprising a plate located between each spring and said supporting means, and a reinforcing spring lying upon each main supporting spring, each main supporting spring being located between said reinforcing spring and said rocking means, each pair of adjusting screws extending through one of said flat supporting springs, one of said reinforcing springs and said rocking means whereby to mount these parts on said supporting means.
8. A check for picker sticks for looms comprising a pair of supporting plates, a pair of main flat supporting springs, means mounting said springs adjacent one end on said pair of supporting plates, said mounting means including a pair of adjusting screws for each spring, rocking means having a raised portion located between each pair of screws, said springs having free ends extending toward each other and forming a V-shaped recess, said reinforcing spring lying upon each main supporting spring, each main supporting spring being located between said reinforcing spring and said rocking means, each pair of adjusting screws extending through one of said flat supporting springs, one of said reinforcing springs and said rocking means whereby to mount these parts on said plates.
